ROBERT HOPE-JONES, OF NORTH TONAWANDA, NEW YORK, ASSIGNOR TO RUDOLPH WURLITZER MANUFACTURING COMPANY, OF NORTH TONAWANDA, NEW YORK, A CORPORATION OF NEW YORK.

KEY MECHANISM FOR ORGANS.

1,203,621.

Specification of Letters Patent.

Patented Nov. 7, 1916.

Application filed September 12, 1910. Serial No. 581,622.

To all whom it may concern:

Be it known that I, ROBERT HOPE-JONES, of North Tonawanda, in the county of Niagara and State of New York, have invented 5 certain new and useful Improvements in Key Mechanism for Organs; and I do hereby declare the following to be a full, clear, and exact description of the same, reference being had to the accompanying drawings, 10 forming a part of the specification, and to the reference-numerals marked thereon.

My present invention has for its object to provide certain improvements in connection with the keys or manuals used in operating 15 organs or similar musical instruments whereby their action may be controlled so that their operation will require the exact "touch" or pressure to be applied to them which the musician may desire.

20 Another object of my invention is to provide a key mechanism, in which each key will be capable of occupying during its movement in one direction, two or more positions for the purpose of successively 25 operating different devices employed for controlling different sets of sound-producing devices for obtaining different musical effects upon successive movements of a single key.

30 My invention also provides means for controlling the action of the key itself so that the passing from one position to another is indicated to the player by the increase in the force of the "touch" pressure required which 35 is at once relieved to permit the key to be held in operated position easily without exertion.

To these and other ends the invention 40 consists in certain improvements and combinations of parts, all as will be hereinafter more fully described, the novel features being pointed out in the claims at the end of the specification.

In the drawings: Figure 1 is a transverse 45 sectional view of the keyboard of a musical instrument showing one embodiment of my present invention; Fig. 2 is a similar view showing a key depressed into the first touch position, and Fig. 3 is a diagrammatic illustration showing parts of an electrically controlled musical instrument illustrating their operation in conjunction with the key mechanism embodying my invention.

Similar reference numerals in the several figures indicate similar parts.

In illustrating my invention I have shown a key-bed composed of the outer or forward rail 1 and the inner or pivot rail 2, separated from the former, both of said rails extending longitudinally between the 60 ends or cheek pieces, one of which is shown indicated by 3. The keys forming part of the action are all similar in construction and for this reason only one of them is 65 illustrated. The key or manual, as it is sometimes called, which is indicated by A rests upon the rail 2 on which it is loosely secured by the pivot pin 4. The outer end 5 of the key which is depressed by the finger of the operator projects beyond the rail 1 70 and the inner or rear end 6 of said key projects in rear of the pivot pin 4 any desired distance.

A key such as described while practicable to any form of musical instrument is adapted particularly to be used in connection with organ actions and of that type known as electric actions in which the speaking of the various pipes and sound producing devices is controlled by the action or mechanism operated by the keys. In electrically controlled organs these devices are in the form of contacts which comprise terminals of normally open circuits which are closed upon the movement of the key, these circuits 80 in turn governing the operation of electro-pneumatic valves controlling the flow of air in the passages employed for effecting the operation of the sound producing devices.

The introduction of electric actions into organs has so greatly relieved the work required to be performed by the key itself, in the previously existing types of organs, that it has been possible to render these keys as 95 quick and responsive in their movement as those of a pianoforte. This, however, carries with it its disadvantages as many organists of the present day are accustomed to the old type of keyboard with its sluggish 100 action, known as "tracker action". Owing to the further fact that in each organ there are several different sets of keys, such as choir, great, solo and swell keyboards, all of which are operated manually, and frequently two or more of them being played 105

upon at the same time, it is desirable that the individual keys be so controlled that they require the performer to exercise a certain amount of force or exertion to move them out of their normal position.

In the present embodiment of my invention I have shown means for retarding the action of the keys comprising a mechanism operated pneumatically, and embodying generally a relief valve connected to the key which is held closed by a pressure of air against it sufficient to counterbalance any predetermined touch pressure which it is desired be exerted on the outer end 5 of the key. As one means of carrying out this object of my invention I have shown a chambered member B arranged in rear of the pivot rail 2 and beneath the ends 6 of the several keys comprising the keyboard. On the lower face of the member B is a valve-seat 7 connected by a small passage 8 to a larger passage 9 in which a partial vacuum is maintained by any suitable form of air pumping or exhausting apparatus, as will be understood. Coöperating with this seat is a valve-head 10 mounted upon the end 11 of a lever pivoted at 12, the other extremity 13 of said lever being connected by a rod 14 to the end 6 of the key, said rod being attached to the lever by a pivot pin 15, and carrying at its upper end an adjustable nut 16 resting against the upper side of the key. Passing through the pivot point 12 of the lever is a pin 17 having at its outer end a spring coil 18, the extremity 19 of which bears against the end 11 of the lever, and is of sufficient tension to normally hold the valve-head 10 against the seat 7 and to restore the key A to its normal position. It will be seen that by this arrangement of the parts the spring 18 may in itself be comparatively weak, but that the atmospheric pressure acting on the outer side of the valve-head 11 will tend to keep the latter against its seat. The pressure required to be exerted on the end of the key to depress it will be proportional to the area of the head 10 and the degree to which the air is rarefied in or exhausted from the passage 9. In practice these parts would be so proportioned that a normal organ action touch equal to about three and a half ounces in weight will be required to move the key downwardly or cause it to dip. A particular advantage is obtained in the use of the co-operating valve and seat for controlling the action of the key, because the movement of the latter is prevented or retarded up to the instant the required pressure is applied on the key, and the valve-head being then moved away from its seat, immediately relieves the tension on the key permitting the operator to hold it in its actuated position with but very slight exertion when holding sustained notes.

In order to produce new musical effects and at the same time reduce the operations which a musician is ordinarily required to perform, such as the drawing of stops and couplers, I have provided a mechanism whereby each key may be employed to operate a plurality of devices arranged to be actuated successively at different points in the movement of the key, each of said devices being adapted to control different sets of sound-producing apparatus.

In the present embodiment of my invention I have illustrated the controlling devices, referred to above, as electromagnetically operated and comprising electric circuits which are opened and closed by the action of the key A, and in this instance I have shown the key as adapted to actuate successively two separate instrument-controlling devices, the first being brought into action by the normal touch applied to the key, the other being a second touch which requires a second or increased touch pressure to be exerted, as will be further described.

One of the main features of the invention resides in providing two or more instrument-controlling devices arranged for successive operation during the movement of the key in one direction. As an example showing the operation of such controlling devices and the manner in which they may be actuated by the keys I have illustrated diagrammatically in Fig. 3 parts of an organ mechanism with which a key of this description may be employed. In this figure C indicates a flue-pipe, such as Diapason, while D indicates a reed-pipe, both connected to their respective wind chests in which are arranged the valve or valves for controlling their operation; c and d represent the electromagnets controlling such valves which are arranged in circuit with the battery X. The circuit controlling the magnet c comprises the wire c' leading to the terminal c², with which coöperates the contact c³ connected by the wire x' to one side of the battery, the opposite pole of the latter being connected to the other terminal of the magnet c by the wire x². The latter is also connected to one end of the coil of the magnet d, its opposite extremity being joined by the wire d' to the terminal d², and adapted to co-operate therewith is the second touch contact d³, also connected to the battery by the wire x³. The contacts c² and d² are both carried on the underside of the key A, and the terminals c² and d², respectively, are so arranged that upon the initial movement of the key the circuit of the magnet c is first completed to cause the speaking of the pipe C; the other set of contacts d² and d³ are so positioned that they are not brought into engagement until the key has been further depressed, nearly to the limit of its move-

ment, at which time the magnet d is energized permitting the pipe D to sound its note.

The contacts last described are illustrated 5 enlarged in Figs. 1 and 2, the terminals being shown as comprising flexible spring fingers or wires mounted in holders 20, one of the latter supporting the terminal c^2 of the first touch set of contacts. These holders 10 are mounted in cradles 21 which are supported at their ends and adjusted as shown, the terminals d^2 of the second touch set of contacts being so positioned that this set may be closed at the proper point in the 15 movement of the key A. The contact members c^2 , d^2 coöperating with the terminals, are each secured at one end to the key by a screw or other fastening device 22, their free ends being adjusted by means of screws 20 23, as will be understood.

In order to arrest the movement of the key in an intermediate position after the contacts c^2 , c^3 have been closed together and before the second set of contacts have been 25 brought into engagement, I employ an arresting mechanism, which interrupts the movement of the key, but will permit the operator to impart a further movement thereto if he so desires. This arresting 30 mechanism performs the function of a yielding stop which, after limiting the initial movement of the key, permits the latter to be further advanced by the exertion thereon of a touch pressure exceeding the 35 pressure required in the first instance to actuate the key.

As a means of carrying out this feature of my invention, I have also shown a pneumatic device comprising a valve seat 24 arranged on the upper side of the chambered member B from which air is exhausted through the passage 25 and trunk 26, the latter corresponding to the passage 9 and either connected thereto or leading directly 45 to a separate apparatus for exhausting the air therefrom. Coöperating with the valve seat 24 is a valve head 27 supported on the lever 28 pivoted at one end as indicated at 29, and having its opposite extremity perforated or slotted, as indicated at 30, to permit the rod 14 to extend therethrough. Adjustably threaded on the rod 14 is the nut 31 forming an engaging shoulder located beneath the end 30 of the lever 28, and adjustable relatively thereto for the purpose 50 of controlling the movement of the key A after it has been depressed and the valve head 10 moved out of engagement with the seat 7, as shown in Fig. 2. The valve seat 55 24 and the head 27 are preferably made larger in area than the corresponding parts 7 and 10 so that for the same amount of suction, or number of inches of vacuum, produced in the passages 9 and 26, the momentum in the key as it is operated by the

first touch pressure will not cause it to overcome the resistance afforded when the nut 31 engages the lever 28. The valve seat 24 and its head 27 are, however, proportioned so that the operator after feeling the resistance interposed to the movement of the key may by an increase in the touch pressure cause the valve head to be lifted and thereupon bring the contact member d^2 into engagement with the terminal d^2 . At this time 75 both sets of contacts will be closed, the first set yielding slightly to maintain a good rubbing contact between them.

It will be seen that when the resistance of the valve head 27 has been overcome and 80 the key depressed to the limit of its movement, it may be held in this position by a light pressure of the operator's finger.

An apparatus embodying my invention 85 comprises but few parts and these may be made small in size and located compactly in the space provided between the rails of the keyed.

I claim as my invention:

1. The combination with a pivoted key, of 90 a chambered member located at one side thereof having valve seats on its opposite faces and provided with passages leading therefrom in which a partial vacuum is maintained, separate valve heads coöperating with said valve seats, pivoted levers each connected with said valve heads, a tension rod connecting one of said levers with said key and extending past the other lever and a shoulder on the rod adapted to operate the last mentioned lever after the first lever has been moved.

2. The combination with a pivoted key, of 95 a chambered member arranged beneath it from which air is exhausted, provided with a valve seat, a valve head coöperating with the latter, a lever pivoted exteriorly beneath the chamber having one end connected to the valve head and its other extremity projecting beyond the side of said chamber and a tension rod connecting the said end of the lever to the key.

3. The combination with a pivoted key 105 for musical instruments, of two restraining mechanisms adapted to counterbalance different predetermined touch-pressures on the key, a connecting member arranged between the key and the mechanism counteracting the lighter touch-pressure and a shoulder on said member coöperating with the other 110 heavier-touch-pressure mechanism during the operative movement of the key and after the restraint of the first mentioned mechanism has been overcome.

4. The combination with a movable key 115 for musical instruments, a chambered member at one side of the key, from which air is exhausted, having two valve seats, and valve heads coöperating with the seats, of 120 separate levers pivoted on the chambered 125

member and connected to said heads for moving them away from their seats, each lever having a free end projecting beyond the edge of the chambered member and a rod connecting the free end of one of said levers to the key for actuating it upon the commencement of the movement of the key and a shoulder on said rod coöperating with the free end of the other lever at a pre-determined point in the movement of the key.

5. The combination with a key for musical instruments, a pivotal support therefor arranged intermediate its length and a chambered member from which the air is exhausted having two valve seats opening in opposite directions, of valve heads coöperating with the seats, levers for operating said heads away from their seats each having an operating end and a rod fastening the key 15 to one lever and having a shoulder adapted

to coöperate with the other lever at an intermediate point in the movement of the key.

6. The combination with a key bed having a pivot rail, a key pivoted thereon and a chambered member located in rear of the rail having valve seats on its opposite faces and provided with passages leading therefrom, and means for producing a partial vacuum in said passages, of separate valve heads coöperating with the valve seats and connections between the rear end of the key and said heads for moving them successively away from their respective seats during the downward movement of the outer end of the key.

ROBERT HOPE-JONES.
